(57) **CLAIM**

The ornamental design for a load transfer plate pocket, as shown and described.

DESCRIPTION

This application is related to the following commonly owned co-pending patent application: U.S. application Ser. No. 16/723,010, entitled "Load Transfer Plate Apparatus". FIG. 1 is a top rear perspective view of a load transfer plate pocket of our new design.

FIG. 2 is a top front perspective view of the load transfer plate pocket of FIG. 1.

FIG. 3 is top view of the load transfer plate pocket of FIG. 1.

FIG. 4 is bottom view of the load transfer plate pocket of FIG. 1.

FIG. 5 is a right side view of the load transfer plate pocket of FIG. 1.

FIG. 6 is a left side view of the load transfer plate pocket of FIG. 1.

FIG. 7 is a rear view of the load transfer plate pocket of FIG. 1.

FIG. 8 is a front view of the load transfer plate pocket of FIG. 1.

FIG. 9 is a cross-sectional view of the load transfer plate pocket of FIG. 1, taken substantially along line 9-9 of FIG. 7.

FIG. 10 is a cross-sectional top perspective of the load transfer plate pocket of FIG. 1, taken substantially along line 10-10 of FIG. 7; and,

(Continued)

FIG. 11 is a cross-sectional bottom perspective of the load transfer plate pocket of FIG. 1, taken substantially along line 11-11 of FIG. 8.

The broken lines in the drawings depict portions of the load transfer plate pocket that form no part of the claimed design.
